UNITED STATES PATENT OFFICE

JOSEPH BERNHARD, OF NEW YORK, N. Y., ASSIGNOR TO CONSOLIDATED TRIMMING CORPORATION, OF NEW YORK, N. Y., A CORPORATION OF NEW YORK

DESIGN FOR A DISPLAY CARD

Application filed April 9, 1932. Serial No. 43,450. Term of patent 3½ years.

To all whom it may concern:

Be it known that I, JOSEPH BERNHARD, a citizen of the United States, residing in New York, county and State of New York, have invented a new, original, and ornamental Design for Display Cards, of which the following is a specification, reference being had to the accompanying drawing, forming a part thereof.

The figure is a perspective view of a display card showing my new design.

I claim:

The ornamental design for a display card as shown.

JOSEPH BERNHARD,
